UNITED STATES PATENT OFFICE

EUGÈNE MATHIEU, OF NEUILLY-SUR-SEINE, FRANCE

CONSTRUCTION OF CARBURETORS

Application filed May 2, 1931, Serial No. 534,466, and in France May 14, 1930.

My invention relates to carburetors for internal combustion engines and it has chiefly for its object to provide an improved mode of construction making it possible to readily 5 mount and dismount the carburetor so as to permit easy access to the main nozzle and to the idling nozzle, and also to the inside of the float chamber, without making it necessary to dismount the pipe that serves to convey 10 the mixture to the cylinders or the air conduit that is eventually connected to the air purifier or the air preheater.

The carburetor according to my invention is formed of two parts connected to each 15 other in a detachable manner. The first part comprises the mixture inlet pipe together with its throttle, the gasoline inlet pipe and eventually the air purifier and/or preheater. The other part comprises the float chamber, 20 the main nozzle, the idling nozzle, and the part of the wall of the inlet conduit that carries these nozzles.

According to another characteristic of my invention, the float is provided on one side 25 with a horizontal guiding organ the ends of which are adapted to slide in grooves provided in the wall of the float chamber, a finger being rigidly connected to said float and bearing against the lower end of the needle 30 valve which controls the gasoline feed.

In order to ensure the free displacement of the needle valve without any possibility of wedging, and to obtain a fluidtight obturation of the gasoline inlet conduit when 35 the needle valve is applied against its seat, said needle valve preferably consists of a rod mounted with a certain play in a bore provided in a boss of the cover of the float chamber and located below the needle valve seat. Said needle valve is adapted to engage a spherical or similar recess provided in a coaxial push piece guided without play in a 40 prolonged part of said bore and on the lower end of which the above mentioned finger rigidly connected to the float is applied.

Another important characteristic of my invention consists in the detachable connection between the two elements of the carburetor.

50 A preferred embodiment of my invention

will be hereinafter described with reference to the appended drawings, given merely by way of example, and in which:

Fig. 1 is an elevational view of the carburetor;

Fig. 2 is a corresponding longitudinal section;

Fig. 3 is a sectional view on the line 3—3 of Fig. 2, and

Fig. 4 is a horizontal section on the line 4—4 of Fig. 2.

The carburetor shown in the accompanying drawings comprises two parts 1 and 2 assembled along joining surfaces *a b c d* of Fig. 1. Part 1 comprises an inlet conduit 3 provided with a flange 4 adapted to be secured to the flange of the inlet pipe leading to the cylinders, and having a right-angular bent portion provided with a flange 5 adapted to be secured to a flange 6 connected to an air purifier 7 (or an air preheater) secured to the engine. The gas throttle 8 is mounted inside conduit 3.

Part 1 is provided with a boss 9 through which passes a gasoline inlet conduit 10, said boss being cast on the inside of the cover 11 of float chamber 12 (said float chamber is a part of unit 2). At the end of conduit 10, a coupling 13 is screwed, said coupling being connected with the gasoline inlet pipe.

Part 2 comprises float chamber 12, a boss 13*a* extending laterally from the wall of said chamber (see particularly Fig. 4) and in which are provided bores for the idling nozzle 14, and a wall 15 supporting the main nozzle 16 and adapted to complete the wall of conduit 3 in the region where said conduit 3 is bent at right angles.

The two elements 1 and 2 are connected to each other in a detachable manner, for instance as follows:

The threaded end 17 of a supporting member is screwed in the central part of boss 9, said support being provided with two lugs 18 provided with apertures 19 adapted to receive a rod 20 the ends of which are pivotally mounted in two bearings 21—22 provided in the wall of float chamber 12. The outer part of rod 20 is bent at 23 so as to form an operating lever, and the central part of said rod, 100

is cranked. The holes 19 are also eccentrically located with respect to the axis of bearings 21-22, so that in the position shown in Fig. 3, part 24 is elastically applied against lugs 18, 5 which keeps the two elements 1 and 2 assembled by an elastic pressure.

By rotating rod 23 through 180°, the cranked part 24 also rotates through 180°, and, in its new position, it is no longer in contact with support 17, owing to the eccentricity 10 of holes 19. To take the carburetor to pieces, it then suffices to pull lever 23 toward the right (Fig. 3) so as to disengage rod 20 from lugs 18.

15 It will thus be seen that it is possible to very easily reach main nozzle 16, idling nozzle 14 and float chamber 12 without having to dismount the inlet conduit 3 leading to the engine and the air purifier or preheater 7.

20 According to another characteristic of my invention, the float 25 carries on one side and at its upper part a support 26 through which passes a guiding rod 27 the ends of which engage grooves 28 provided in the wall 25 of float chamber 12. Support 26 is provided with a finger 29 extending toward the center of the float and adapted to control the displacements of needle valve 30.

Said needle valve 30 cooperates with a seat 31 integral with a piece 32 screwed in boss 9, and whose central bore, through which needle valve 30 is adapted to move, has a greater diameter than said needle valve, so as to provide an annular passage 33 for the gasoline, 35 said gasoline being evacuated through inclined conduits 34. The lower end of needle valve 30 has a spherical or equivalent shape and rests in a spherical recess of the head 35 of a push piece 36, the lower end of which 40 projects from piece 32, so as to be in contact with finger 29. Head 35 is guided without play in the central bore of piece 32, and the hole through which passes the lower end of push piece 36 has a smaller diameter than 45 head 35 so as to prevent said push piece from leaving piece 32.

The operation of that device is as follows:

When the level of gasoline in float chamber 12 is below the normal level N-N, float 25 50 moves down by pivoting about rod 27, the ends of which are applied against the bottoms of grooves 28. It results therefrom that arm 29 rotates in an anti-clockwise direction and allows needle valve 30 to move down 55 away from its seat 31, which causes gasoline to flow from conduit 10 into float chamber 12.

When the gasoline level rises in float chamber 12, the float moves in an upward direction and finger 29 lifts needle valve 30 until 60 it is applied against its seat. During that movement finger 29 bears against push piece 36, and rod 27 remains applied against the bottom of groove 28 owing to the position of the center of gravity of the float. If necessary, the ends of guiding rod 27 can be up-

wardly bent so as to fill up grooves 28 the upper ends of the bent parts of said rod being then applied against the under side of cover 11.

It is pointed out that, owing to that mode 70 of construction, the taking to pieces of the carburetor is greatly facilitated. It is only necessary to separate cover 11 from float chamber 12 to remove float 25 by taking hold of finger 29. The different organs that go 75 to form the needle valve are also very easy to reach, it being given that it suffices to unscrew piece 32.

Owing to the combination of needle valve 80 30 and of push piece 36, the needle valve is guided in the correct manner without any possibility of jamming, while leaving a free space for the flow of gasoline, and it moves always parallelly to itself, which ensures a fluid-tight obturation of the gasoline inlet 85 conduit, in spite of the pivoting motion of finger 29.

While I have disclosed what I deem to be the preferred form of my device, I do not wish to be limited thereto as there might be 90 changes made in the arrangement, disposition and form of the part; for instance the device for connecting together the two units that form the carburetor, the mode of construction of the float chamber, with its float and 95 its needle valve might be used in connection with the other types of carburetors without departing from the principle of my invention as comprehended within the scope of the appended claims.

100 What I claim is:

1. A carburetor comprising two separate units, one unit comprising a float chamber, a main nozzle, an idling nozzle, said unit also comprising means for supporting said nozzles, the other unit comprising a conduit for conveying the mixture to the engine manifold, a throttle in said conduit, a cover for the float chamber, and a gasoline inlet conduit provided in said cover, the carburetor further comprising a boss projecting downwardly from said cover and provided with a hole, an elastic crank rod for engaging said hole and slidably and pivotally mounted in the walls of the float chamber about an axis 110 distinct from the axis of said hole, said rod extending exteriorly of said float chamber and being bent substantially at right angles 115 so as to form an operating lever, whereby the two units can be readily assembled together or separated from each other.

2. A carburetor according to claim 1 further comprising a needle valve for controlling the gasoline feed and projecting downwardly from said cover, a float pivotally mounted in said float chamber, and a finger rigidly mounted on one side of the upper part of said float adapted to cooperate with 120 said needle valve.

3. A carburetor comprising a float cham-

ber, provided with two vertical grooves in its inner surface, a cover for said float chamber, a gasoline inlet conduit in said cover, a bore through said cover extending downwardly from said conduit, a plurality of inclined conduits connecting the intermediate part of said bore to the inside of said float chamber, a needle valve having a diameter substantially smaller than that of said bore

10 slidably mounted therein, a seat for said needle valve at the upper part of said bore, the lower end of said needle valve being rounded, a push piece having a diameter substantially equal to that of said bore slidably

15 mounted therein below said needle valve, the upper part of said push piece forming a rounded recess adapted to cooperate with the lower part of said needle valve, a float in said float chamber, a finger rigidly secured

20 to the upper part of said float, a guiding rod secured to said finger with its ends engaging said grooves, said finger being adapted to cooperate with the lower end of said push piece.

25 4. In a carburetor, a float chamber, a cover for said float chamber, a gasoline inlet conduit provided in said cover and disconnectable means for assembling said chamber and said cover, said means comprising an elastic

30 transverse rod pivotally and slidably mounted in the walls of the float chamber, a central boss projecting downwardly from said cover, and provided with a hole, the axis of which is eccentric with regard to said rod, said rod

35 having a crank engaging said eccentric hole and means for operating said rod from the outside.

5. A carburetor comprising a float chamber provided with two vertical grooves at

40 the top of its inner surface, a cover for said float chamber, a gasoline inlet conduit in said cover, a needle valve slidably mounted in said cover for controlling the flow of gasoline through said gasoline inlet conduit, a float in

45 said float chamber, a finger rigidly secured to the upper part of said float, a rod guided in said cover for transmitting the motion of said finger to said needle valve and a horizontal guiding rod secured to said finger

50 with its ends engaging the bottom of said vertical grooves, whereby said float is pivotally mounted in said float chamber.

In testimony whereof I have signed my name to this specification.
